UNITED STATES PATENT OFFICE.

JOSEPH N. MORGAN, OF WALLACE, INDIANA.

GATE.

SPECIFICATION forming part of Letters Patent No. 478,451, dated July 5, 1892.

Application filed February 18, 1892. Serial No. 422,050. (No model.)

To all whom it may concern:

Be it known that I, JOSEPH N. MORGAN, of Wallace, in the county of Fountain and State of Indiana, have invented certain new and 5 useful improvements in Gates; and I do hereby declare the following to be a full, clear, and exact description of the invention, such as will enable others skilled in the art to which it appertains to make and use the same.

10 My invention relates to an improvement in gates, and more particularly to that class of gates employed on farms, the object being to provide means for increasing the opening when it is desired to accommodate vehicles or 15 machinery of unusual size or of a size too large to pass through an ordinary farm-gate.

A further object is to construct and arrange the gates in such manner that one of said gates will act as an abutment for the other.

20 With these ends in view my invention consists in certain novel features of construction, and combinations of parts, as will be herein-after more fully described, and pointed out in the claims.

25 In the accompanying drawings, Figure 1 is a view embodying my invention, showing the gates closed; and Fig. 2 is a view of a modification.

A A' represents two sections of a fence, and 30 B B' the posts thereof, to which latter gates C C' are hinged at their outer edges. To one side of the post B is located a post a, to which is secured brace E, which extends diagonally upward and is supported between its ends by the post B. The upper end of said brace E is provided with a pulley b. At a point between the ends of post B an arm E' is secured, which latter extends upwardly and is provided on its outer or free end with a pulley 35 b'. Opposite post a is located a post a', to which is secured an upwardly-projecting arm E², the outer end of which is provided with a pulley a². A continuous piece of wire e is secured to the brace E and arms E' and E² in the manner shown in the drawings, which 40 serves to tie said arms together and brace the same.

A rope d is first passed through pulley b', thence through pulley b, and then through a 45 staple located near the upper part of the free end of gate C, and is finally fastened to the

latch f, which latter works in a keeper g, located on the free end of gate C'. The other or free end of said rope is provided with a handle h. A rope d' is passed through the 55 pulley a², and is secured to rope d in close proximity to the pulley b, and its outer end is provided with a handle h'.

The posts B' B² are provided with brackets D D', in which is supported a rail or bar F, one 60 end of which is pivotally connected to the free edge of the smaller gate C', said rail projecting a slight distance beyond the edge of gate C' to form an abutment for the larger gate C. The lower end of the outer rail or strip of the 65 small gate C' is provided with a hook j, which engages a staple k, located in the upper end of post l, for the purpose of locking the gate against an inward movement, said post l also serving as an abutment for the smaller gate C'. 70 To the lower edge of the upright or strip of the small gate an overlapping plate o may be secured to serve as an abutment for the larger gate C and prevent any tendency of the gates to swing inward.

75 In the modification shown in Fig. 2, m is a post provided on one side near its top with a staple m' for the reception of a hook m², secured to one end of a brace n, the opposite end of said brace being pivotally attached to the upright portion of the free end of the gate C'.

When it is desired to allow the passage of ordinary vehicles through the gate, it is only necessary to open the large gate, which is accomplished by applying power or pulling on either of the handles h or h'; but should it be necessary to increase the opening to accommodate vehicles or machinery larger than the open space afforded by gate C, the smaller 85 gate C' will be opened, which is done by simply releasing the rail or bar F (or hook m² in the modified form) and unhooking the gate from the post l, when the gate will swing to its open position.

90 It is evident that changes in the construction and relative arrangement of the several parts might be made without avoiding my invention, and hence I would have it understood that I do not restrict myself to the particular 95 construction and arrangement of parts shown and described; but,

Having fully described my invention, what I claim as new, and desire to secure by Letters Patent, is—

1. The combination, with a large and a small gate hinged at their outer edges and a latch carried by the larger gate, of a keeper on the smaller gate for the reception of said latch, and a pivoted bar for locking said smaller gate independent of the larger gate, substantially as set forth.

2. The combination, with a large and a small gate hinged at their outer edges and a latch carried by the larger gate, of a keeper on the smaller gate for the reception of said latch, and a pivoted bar for independently locking

10 said smaller gate, said bar constituting an abutment for the larger gate, substantially as set forth.

3. The combination, with a fence and two gates hinged thereto, of a locking-bar connected with one gate and with the fence and forming an abutment for the other gate, substantially as set forth.

20 In testimony whereof I have signed this specification in the presence of two subscribers.

25 JOSEPH N. MORGAN.
